UNITED STATES PATENT OFFICE.

CALVIN JACKSON, OF READING, PENNSYLVANIA.

DESIGN FOR A CIRCULAR-CUTTING TOOL.

SPECIFICATION forming part of Design No. 31,753, dated October 31, 1899.

Application filed September 22, 1899. Serial No. 731,357. Term of patent 14 years.

To all whom it may concern:

Be it known that I, CALVIN JACKSON, a citizen of the United States of America, and a resident of Reading, in the county of Berks and State of Pennsylvania, have invented and produced a certain new and original Design for a Circular-Cutting Tool, of which the following is a specification.

My invention relates to a design of circular-cutting tool for metal-working lathes.

Referring to the drawings, Figure 1 is a longitudinal elevation, and Fig. 2 an end view, illustrating my design, the essential features of which are the circular notched cutter-disk

or head *a*, the conical threaded shank *b*, and the intermediate cylindrical body *c*, the notch *a'*, removing a portion of the spiral cutter-rib *a²* of the head, and the body *c*, having wrench-flattenings *c'*.

What I claim is—

The design for a circular-cutting tool substantially as shown and described.

Signed by me at Reading, Pennsylvania, this 18th day of September, A. D. 1899.

CALVIN JACKSON.
